METHOD AND APPARATUS FOR FORMING
CONCRETE PIPES

Hector X. Eschenbrenner, Columbus, Ohio

Application August 11, 1947, Serial No. 767,928

3 Claims. (Cl. 25—30)

1

The present invention relates to apparatus and methods for forming concrete pipe, and has particular reference to improved apparatus and methods for the formation of concrete pipe from what is termed a "wet" cementitious mix which has long been known to produce concrete articles possessing a high degree of strength, durability, and a superior surface finish.

Heretofore, in the formation of concrete pipe with machines it has been customary to utilize what is known in the art as "dry" mix, wherein the liquid content of the mix was held to a substantial minimum, in order that after initially forming the pipe the same might possess sufficient rigidity to retain its shape and be able to stand alone upon the early removal therefrom of the associated inner form apparatus, and without necessitating a lengthy setting or drying period prior to such removal. Also in the formation of concrete pipe from a "dry" mix, it was necessary to tamp or pack the mix as the same was being introduced to the forming apparatus, in order that a uniform density might be had throughout the finished pipe. The apparatus necessary for such tamping operation was generally subject to many objections, due to its cumbersome nature, its susceptibility to breakage, and its interference with the metallic reinforcing members generally positioned within the mix as the same was being formed into pipe configuration. Further, the exterior surfaces of pipes formed from a "dry" mix were characterized by their rough finish, which was objectionable from the standpoint of sanitary engineering, as such roughness subsequently tends to disturb the flow of liquids through such pipe and enhances the accumulation of moss and other foreign matter upon the inner surfaces of the pipe.

In the past, the primary objections to forming concrete pipe from what is generally termed a "wet" mix, wherein the liquid content of the mix is in excess of that actually required for the normal setting and molding of the cement, arose through the difficulty of removing the excess liquid during or after initial forming operations. Failure to remove substantially all of the excess liquid from the mix resulted in a greatly increased setting time prior to the removal of the associated forms from the molded pipe, because of the fluid or semi-fluid nature of the overall mix. Also, the presence of excess liquids during hardening stages tended to produce a brittle and somewhat weakened pipe, due to the formation of occluded air spaces within the mix upon evaporation of the excess water present therein.

2

Accordingly, it is an object of the present invention to provide improved apparatus and methods for forming concrete pipe possessed of superior characteristics, as to structural strength and surface finish, by utilizing a so-called "wet" cementitious mix, wherein the excess liquids carried within the mix are removed during initial forming operations through the medium of negative pressures applied through at least one of the form members of the associated molding machine to substantially the entire inner surface of the mix while the same is undergoing rotational movement to insure an even density throughout the finished pipe.

It is another object of this invention to provide a concrete pipe-forming machine wherein the usual tamping apparatus, characterized by its many objectionable features, is eliminated entirely, due to the fluid nature of the "wet" mix, and its ability to uniformly pack itself into a dense mass independently of such tamping apparatus.

It is a further object of this invention to provide a concrete pipe-forming machine embodying an outer cylindrical and rotatable form, and a relatively stationary cylindrical inner core disposed in concentrically spaced relation to the outer form and defining therewith a cylindrical pipe-forming chamber for the reception of a "wet" cementitious mix, and wherein the core of the machine is formed internally with a suction chamber communicating with the pipe-forming chamber for withdrawing excess water from a "wet" mix disposed therein during the initial formation and rotation of the pipe-forming mix.

It is still another object of this invention to provide improved methods for the formation of concrete articles possessing superior characteristics by subjecting a cementitious mix upon initial formation to rotational movement to insure an even and uniform density throughout the mix, at the same time subjecting substantially the entire surface of the mix to reduced pressures to remove excess liquids therefrom, and simultaneously vibrating the mix to additionally insure superior density qualities within the object to be formed.

Yet another object of this invention is to provide means whereby the action of reduced pressures upon the mix is evenly distributed over the entire area of the mix rather than being alternately concentrated upon any one particular area, in order to avoid uneven displacement of the mix in patches throughout the formed article.

For a further and more detailed understand-

ing of the present invention and the additional objects and advantages arising therefrom, reference is made to the following description and the accompanying drawings wherein:

Fig. 1 is a side elevational view of a concrete pipe-forming machine embodying the aspects of the present invention;

Fig. 2 is a front elevational view of the machine disclosed in Fig. 1;

Fig. 3 is an enlarged medial transverse vertical sectional view taken through the core, outer form, and turn table mechanisms embodied in the present pipe-forming machine;

Fig. 4 is a horizontal sectional view taken along a plane indicated by the line 4-4 of Fig. 3;

Fig. 5 is an elevational view of the cylindrical core embodied in the present machine;

Fig. 6 is a horizontal sectional view taken along the line 6-6 of Fig. 3;

Fig. 7 is a fragmentary vertical sectional view taken through a slightly modified assembly, wherein the cylindrical outer form is perforated.

Referring now to the drawings, the numeral 10 designates the frame structure of the present pipe-forming machine, which structure comprises a plurality of vertically arising side members 11, and a number of upper cross members 12. The vertically arising end members of the frame are embedded in and supported by a floor-level foundation 13. Arranged slightly above the foundation 13, in a horizontal plane, is a circular turn table 14 which is supported for rotational movement within an axially disposed stationary bearing member 15 carried below the floor level upon suitable subterranean angle iron beams 16. The table is formed centrally with a circular bearing sleeve 14b which fits within the bearing member 15 to provide for rotational movement within the table relative to the bearing member. An annular thrust bearing 15a is interposed between the upper surface of the member 15 and the lower surface of the turn table to minimize friction between these parts. The turn table 14 is further provided at its underside with a beveled ring gear 17 which is maintained in meshing engagement with the teeth of a smaller beveled pinion 18 carried upon the outer end of a driven shaft 19. The shaft 19 is, in turn, driven through a series of reduction gears 20 whose driving power is furnished by an electric motor 21 suitably supported upon the frame structure 10.

Disposed upon the upper cross members 12 of the frame is a motor driven winch 22, which, through a system of cables and pulleys, supported by a suitable mast structure 23, serves to elevate or lower the core of the machine which is carried upon the lower end of a vertically disposed lift-shaft 24. The shaft 24 is guided, in the usual manner, during its descent and elevation, by means of a cross head 25 extending between and guided within a pair of transversely spaced guide slots disposed within an opposing pair of the vertically arising side members 11 of the frame. The shaft 24 is disposed in vertical axial alignment with the rotatable turn table 14, in order that the core structure carried at its lower end may descend and arise in axial alignment with the table.

The upper surface of the turn table 14 is formed with a plurality of cleats or lugs 14a upon which is supported the lower edge of a cylindrical outer form member 26. The outer form 26, as is the usual case, is divided into a pair of semi-circular hingedly mounted or de-

tachable sections which are united by means of externally disposed locking devices 27. The outer form 26 is adapted to be positioned in vertically arranged order upon the lugs of the turn table 14, and is maintained in axial alignment therewith by means of positioning studs 28 carried upon the upper surface of the lugs 14a. As before stated, a cylindrical core 29 is rigidly carried at the lower end of the vertically arranged shaft 24, and is movable in a vertical plane in alignment with the axis of the turn table 14. The diameter of the core 29 is substantially less than that of the outer form 26, and when lowered to its pipe-forming position, as disclosed in Fig. 3 of the drawings, the same is disposed in spaced concentric relation to the outer form, and thereby defines with the outer form an annular cylindrical chamber 30 for the reception of a wet cementitious mix which is introduced within the chamber by way of a feed spout 31 communicating at its upper end with a feed hopper 32 which is carried by the frame structure, and from whence the mix may be discharged to the spout by means of a suitable manually controlled metering valve, as indicated at 32a.

As shown in Fig. 3 of the drawings, the lower end of the mix-receiving chamber 30 is closed by an annular pallet 33 which is detachably supported upon an annular ledge 34 which is secured to the lower inner surface of the outer form 26. The pallet 33 possesses a substantially Z-shaped cross sectional configuration and serves to support the lower end of the column of mix positioned within the chamber, and to form the lower end into spigot configuration corresponding to the enlarged upper bell-end of the finished pipe provided by a relatively enlarged flange 35 carried by the upper end of the core. By this means, the individual pipe sections formed within the machine are provided with cooperatively fitting bell and spigot ends. The pallet 33 is formed so as to closely conform to the outer diameter of the core 29, in order to prevent leakage of the wet mix from the lower end of the chamber 30, during initial pouring and subsequent rotation of the mix and outer form.

The upper end of the cylindrical core 29 is closed by means of an imperforate upper end plate 36, to which is secured, by means of a sleeve 37, the lower end of the lift shaft 24. The side walls of the core are formed with a series of vertically aligned perforations 38 which provide communication between the mix-receiving chamber 30 and the interior chamber of the hollow core. The interior bottom wall 39 of the core is inclined toward its center, at which point the lower wall 39 is provided with an axially disposed passageway 40 which is defined by a downwardly extending and axially disposed sleeve 41 formed integral with the bottom wall. The lower portion of the sleeve 41 is receivable in, and forms a slip joint with a bell shaped socket member 42 carried by and disposed axially of the main bearing member 15. A compression gasket 43 is disposed at the lower tapered shoulders of the socket member 42 to provide an air-tight seal between the two members when the core 29 is lowered into position, as indicated in Fig. 3. The socket member 42 is formed with a tubular extension 44 which extends below the main bearing member 15 and its supporting angle iron means 16, to connect with a suction conduit 45, by means of a threaded joint 46. The opposite end of the suction conduit 45 is connected with and forms the intake side of a suit-

able motor driven suction pump 47 positioned within a subterranean sink 48 disposed below the floor level foundation 13, upon which the machine is supported. Thus it will be seen, that as the core 29 is lowered to its pipe-forming position, as indicated in Fig. 3, an air-tight communication is obtained between the interior chamber of the core and the suction pump 47, and upon operation of the latter the pressure within the interior of the core will be reduced whereby substantially the entire inner surface of a body of cementitious mix positioned within the chamber 30 will be subjected to negative pressures, upon rotation of the outer form and the mix, to draw off or remove excess liquids within the mix by way of the perforations 38, and downwardly and outwardly through the centrally disposed passageway 40 to be discharged from the suction pump 47. To prevent the discharge or withdrawal of solid particles from within the mix disposed within the chamber 30, the interior surface of the side walls of the core is provided with a screened or mesh covering 49 which prevents the passage of solid materials through the perforation, but at the same time allows excess liquid to be drawn off by means of the reduced pressures within the interior of the core. Also disposed within the core 29, and rigidly attached to the interior side walls thereof, is an electrically operated high frequency vibrator mechanism, indicated by the numeral 50. Electrical current is supplied the vibrator mechanism by means of an electrical lead conduit 51 introduced interiorly of the core through a sealed opening 52 provided in the upper end wall 36 thereof. The vibrator mechanism 50 serves upon operation to impart high frequency vibrations within the core 29 whereby the adjacent cementitious mix is subjected to such vibration to improve the subsequent density qualities within the finished pipe formed by the present machine.

It will be seen, that due to the simultaneous application of reduced pressures to the mix during rotation thereof, with the added feature of vibration, substantially the entire inner surface of the mix disposed between the inner and outer forms is subjected to the reduced pressures as the mix revolves past the perforated areas of the core, the same being subjected to a constant churning action due to the relative movement between the mix and the stationary core, thus insuring an even mixture resulting in a pipe section possessing uniform density from top to bottom.

In operation, the perforate inner core 29 is first lowered to its operating position, as disclosed in Fig. 3, thereby establishing an air-tight communication between the interior chamber of the core and the suction pump 47. At this time, the outer form 26 and its associated pallet 33 are assembled in their respective order upon the turn table 14 in spaced concentric relation to the outer walls of the core, and defining therewith the annular cylindrical mix-receiving chamber 30. Rotation is then imparted to the turn table 14, by means of its associated electric motor, whereupon the outer form and pallet are caused to rotate about the relatively stationary core, at which time a wet cementitious mix is introduced within the chamber 30, during the rotation, in an even and metered flow by way of the feed spout 31. It will be understood, that due to the rotation of the outer form and its associated pallet during the metered introduction of the mix

through the feed spout, the level of the mix within the chamber 30 will be evenly distributed constant, thereby insuring a predetermined rise of the mix per revolution of the outer form which causes the mix to be packed into a uniform and dense mass from the bottom to the top of the chamber. During the initial filling of the mix-receiving chamber, considerable excess liquid will be drained from the mix through the perforations of the core and will pass by gravity outwardly through the suction pump 47. As the level of the mix within the chamber rises above the upper perforations of the core, the metering valve 32a, associated with the feed hopper 32, is closed to curtail the flow of mix within the chamber. At this time the suction pump 47 is operated to provide decreased pressures within the core during the rotation of the mix and the outer form, whereby excess liquids are forced by atmospheric pressure present at the opposite side of the mix, inwardly through the perforations of the core to be sucked downwardly and outwardly of the interior chamber by way of the suction passage 40, and to be ultimately discharged from the pump 47. This operation should be allowed to continue for a sufficient time to insure the removal of substantially all of the excess liquid present within the mix. At this time, the mix within the chamber 30 should be sufficiently dry and should possess sufficient body and strength to be able to retain its shape upon removal of the core therefrom. After the complete evacuation of the excess liquid from the mix, rotation of the turn table is precluded, and the pump 47 stopped, at which time the core 30 is elevated by the winch mechanism 22 to leave the initially preformed pipe section standing upon the pallet 33 and within the outer form 26. During the elevation of the core, the lowermost peripheral edge of the core, which is unperforated, will tend to smooth the inner surface of the preformed pipe section as the same is withdrawn through the center thereof, it being understood that a certain amount of roughness within the inner surface of the pipe accompanies the rotation thereof past the perforations of the core, but as the latter is withdrawn upwardly the smooth lower edge of the core tends to seal and finish the inner surface of the pipe. The initially formed pipe section, with its associated pallet and outer form may then be removed to a remote position from the machine to allow the same to finally set and cure before the removal therefrom of the outer core and the pallet. At this time the machine may again be assembled with the aid of an additional outer form and pallet to perform the operating cycle just described.

While the cylindrical outer form 26 of the present machine has been disclosed in an imperforate form, the same may be advantageously formed in a perforate condition, as shown in Fig. 7 of the drawings. In this form, an outer perforated form 53 replaces the heretofore described imperforate outer form, and may be advantageously provided on either side with a web of screening material disposed adjacent its perforations in order to prevent the passage of solids therethrough. The use of this type form enables a certain amount of the excess liquids within a wet cementitious mix to pass both by gravity, during initial filling operation, and by centrifugal forces set up within the mix during the rotation thereof, from the body of mix, as well as being drawn out by the suction process. Further, the

use of a perforate outer form provides an increased area upon which atmospheric pressures will act to facilitate the withdrawal of excess liquids through the core.

In the foregoing specification, the terms "wet" and "dry" mix are intended to differentiate between the relative percentages of water used in different types of mixes, or in other words, the water ratio of a mix. Normally, a "dry" mix contains approximately three gallons of water per one hundred pound bag of cement, and produces a relatively cohesive non-fluid mass, whereas a "wet" mix contains approximately five to six gallons of water per one hundred pound bag of cement. As a percentage ratio, a "dry" mix approximates one part water to five parts by weight of cement, and "wet" mix approximates one part water to three parts by weight of cement, and provides a generally semi-fluid mass capable of assuming the shape of a receptacle into which it may be poured. The term "cementitious mix" is intended to include all types of mixes which contain the essential constituent of cement, whether sand, gravel, stone, asbestos or other fibres be added with the cement and water constituents. The present machine and methods readily lend themselves to the production of asbestos pipe, wherein no stone is employed in the original mix, such pipe being generally known commercially under the trade name of Transite.

In view of the foregoing, it will be seen that the present invention provides a mechanically efficient, useful, and novel machine for the production of concrete pipe from "wet" cementitious mixes. Further the present invention sets forth useful and efficient methods for forming concrete pipe from such mixes, the same providing for the formation of concrete pipe and other molded bodies possessed of extremely high structural strength, and having a smooth and even surface finish. In use, machines formed in accordance with the present invention entirely eliminate the necessity for complex and mechanically inefficient tamping or packing apparatus, thereby considerably reducing the cost of manufacture and operation of pipe-forming machines of the character heretofore utilized in the industry. Also, by using negative pressures in conjunction with the wet mix, the initial forming period of the pipe is greatly reduced as compared with present day methods, which results in economical and efficient overall operations. Further, the present invention contemplates a multiple station machine embodying a plurality of pipe-forming assemblies utilizing common driving and pressure reducing apparatus. The present invention is also characterized by its adaptability to use with previous types of pipe-forming machines by simple modification to the core structure, the turn table, and the addition of the suction-creating apparatus.

While a preferred form of the present invention has been disclosed in detail, it will be manifest that various modifications, as to details of construction, are possible without departing from the scope of the following claims.

I claim:

1. In a concrete pipe-forming machine; a substantially horizontally disposed rotary turntable; a vertically arranged cylindrical outer form carried for rotation with said turntable; a socket member positioned axially of said turntable; a vertically arranged cylindrical inner core formed with a perforate side wall and a substantially enclosed inner chamber in communication with the perforations of the side wall; means connected

with the upper end of said core for moving the latter axially of said outer form, said core being movable to a position of spaced concentricity with respect to said outer form and defining therewith an annular pipe-forming chamber for the reception of a cementitious mix; conduit means projecting axially outwardly from the lower end of said core and communicating with the inner chamber thereof, said conduit means being receivable within said socket member when said core occupies its position of concentricity with respect to said outer form; and vacuum-producing means communicating with said socket member and operable to establish subatmospheric pressures within the inner chamber of said core upon engagement of said conduit means and said socket member whereby to draw off excess fluids present in a cementitious mix positioned in said pipe-forming chamber adjacent the perforate side wall of said core first inwardly of the chamber of said core and then outwardly through said conduit means.

2. The method of forming concrete pipe which comprises introducing a fluid cementitious mix containing an excess amount of liquids within a pipe-forming chamber defined by a plurality of relatively spaced forms; moving said mix around one of the forms while simultaneously applying subatmospheric pressures to surfaces of the mix adjacent said one of the forms to extract excess fluids from said mix and to compact the same within the chamber; withdrawing the excess fluids extracted from the mix from the pipe-forming chamber; and continuing the movement of said mix relative to said one of the forms until said mix attains a plastic semi-solid consistency.

3. The method of forming concrete articles which comprises depositing a fluid cementitious mix containing an excess of plasticizing liquids within a molding chamber defined on one side by a stationary form; causing said mix to move relative to and in contact with said stationary form to compact said mix within said chamber; subjecting said mix during movement thereof to subatmospheric pressures acting through said stationary form to extract excess liquids therefrom; and withdrawing excess liquids extracted from said mix from said chamber and continuing the movement thereof relative to said stationary form until said mix attains a plastic semi-solid consistency.

HECTOR X. ESCHENBRENNER.
